CLAIM

The ornamental design for a golf club head, as shown and described.

DESCRIPTION

FIG. 1 is a front elevational view of the golf club head;
FIG. 2 is an enlarged front elevational view thereof;
FIG. 3 is an enlarged view of area 3 in FIG. 2;
FIG. 4 is a cross-sectional view thereof taken along line 4-4
in FIG. 3;
FIG. 5 is a top plan view thereof;
FIG. 6 is a bottom plan view thereof;
FIG. 7 is a toe-side elevational view thereof;
FIG. 8 is a heel-side elevational view thereof; and,
FIG. 9 is a rear elevational view thereof.

The broken lines depict unclaimed portions of the golf club head, and thus form no part of the claimed design. The dot-dot-dash chain lines depict the boundaries of enlarged areas, and thus form no part of the claimed design.
